UNITED STATES PATENT OFFICE

LATIMER D. MYERS, OF CINCINNATI, OHIO, ASSIGNOR TO THE TWITCHELL PROCESS COMPANY, OF ST. BERNARD, OHIO, A CORPORATION OF OHIO

PROCESS OF SULPHONATING MINERAL OIL

No Drawing.

Application filed March 2, 1929. Serial No. 344,100.

This invention relates to a process of treating mineral oil to produce medicinal white oil or the light colored technical oils and mineral oil sulphonates.

5 Specifically, this invention is directed to a process which is an improvement over the process disclosed in Petroff Patent No. 1,087,888, issued February 19, 1914, Humphrey Patent No. 1,286,179, issued November 26, 1918, 10 and other known and used processes. According to the above specified patents mineral oil such as a lubricating stock is treated with fuming sulphuric acid repeatedly. After each treatment, the sludge is drawn off and 15 after repeated treatments mahogany sulphonates are extracted from the oil layer leaving a remainder of relatively clear oil or white oil, and water soluble sulphonates are extracted from the sludge layer. The products 20 of these processes are, therefore, white oil, mahogany sulphonates, or oil soluble sulphonates, and water soluble sulphonates. The mahogany sulphonates have been used for many years past as saponifiers in the soap, 25 stearic acid and glycerine producing industries. The sludge layer sulphonates are at present extensively used for decomposing or resolving the petroleum and water emulsions encountered in the oil fields. Other uses for 30 these sulphonates are developing and they are becoming of increasing commercial importance.

So far the refining operations have been carried on solely from the point of view of 35 producing white oil, and the sulphonates have been treated as inconsequential by-products. The present inventors have, however, investigated the refining operations with the view of altering and adjusting them to produce 40 greater yields of the sulphonates without interfering with the yield of white oil, and without increasing the cost of the operation out of proportion to the benefit obtained.

It has been recognized in the past that frequent 45 extractions of the sulphonates from the oil layer, as distinguished from a single extraction at the end of the sulphonating treatment, augments the yield of oil layer sulphonates. This, however, increases the cost of the 50 operation very materially. The inventors

have, therefore, investigated the character and strength of the acid to be used and also the temperature at which the sulphonation is carried on with the view of obtaining higher yields of the sulphonates without extracting 55 them from the oil layer oftener than every second or third sulphonation. In general, experiments show that increase in the strength of the fuming sulphuric acid results in greater production of mahogany sulphonates, but 60 also results in greater destruction of the mahogany sulphonates upon second treatment with the fuming acid. Sulphonating at elevated temperatures increases the yield of mahogany acids and does not bring about any 65 greater decomposition of the mahogany acids on the second treatment with fuming sulphuric acid, but the use of too high a temperature results in the coking of the sludge sulphonates which renders them worthless. 70

The problem of the inventors was, therefore, to determine the strength and type acid and the temperature most expedient for producing a high yield and a desirable balance of mahogany sulphonates and sludge sulphonates without requiring too frequent extraction 75 of the mahogany sulphonates from the oil layer. The following example is therefore given to illustrate this invention, though it must be understood that minor departures can 80 be made from the exact temperatures and acid strengths specified without sacrificing the novel increment of yield of sulphonates.

A high gravity petroleum distillate such as 85 a heavy lubricating stock, preferably from a naphthenic or a mixed base crude oil, is treated with 5% its weight of concentrated sulphuric acid after which the oil is allowed to stand until the asphaltic and resinous materials contained in the oil have precipitated. 90 This requires from three to four hours on a low gravity oil, and up to twenty-four hours on a heavy viscous oil. The settling is accelerated by maintaining the oil at a temperature such as 50° C. The oil is then separated 95 from the material which settled out, and its surface is sprayed with fuming sulphuric acid. During this spraying operation, the oil is preferably agitated either by dry air or by mechanical devices. This fuming sul- 100

phuric acid contains between 25 and 35%, or preferably 30%, free SO₃ as this concentration of oleum has been found to give the greatest yield of mahogany sulphonates based on available SO₃ used and does not cause excessive decomposition of the mahogany acids on the second treatment.

For any single sulphonation treatment approximately 20% of fuming sulphuric acid is used, the 20% being based on the weight of the oil treated. During this sulphonation the oil is held in most cases at a temperature between 50 and 60° C. This has been found to be the maximum temperature that can be employed for most oils. Although sulphonation at a higher temperature results in an increased yield of mahogany acids the sludge acids are reduced to coke. The fuming sulphuric acid is added as rapidly as consistent with the conservation of the sulphur trioxide, though care must be taken that the heat developed by the reaction be not so great as to coke some of the material.

After the fuming sulphuric acid has been added, the oil is allowed to stand until the sludge has completely precipitated. A temperature such as 50° C. is suitable for the settling. The sludge is then drawn off and the oil is subjected to a second sulphonation similar to the one just described. After the second sludge has been drawn off, the oil is thoroughly mixed with 50% of its weight of 66% strength aqueous methyl alcohol, and sufficient sodium carbonate or an equivalent amount of some other alkali to neutralize the mineral oil sulphonates and free sulphuric acid contained in the oil. The aqueous alcohol dissolves these sulphonates since they are preferentially soluble in it.

Other alcohols and water mixable organic solvents can be used in place of the alcohol specified. The aqueous alcohol containing the dissolved sulphonates and the oil are then allowed to separate by gravity or are run through a centrifuge. The latter is recommended as it effects a more complete separation of the oil and sulphonates since there is a physical attraction between particles of the oil and the sulphonates which is not completely overcome by the force of gravity, but can be overcome in the centrifuge. The oil is then subjected to further sulphonations, settlings, and extractions as outlined above, and this treatment is continued until the oil after extraction is sufficiently light in color for the purposes required. The sludge sulphonates are extracted by various methods known to the art.

When the process described above is followed, the yield of valuable mahogany sulphonates is very much higher than the yield provided by following the disclosure of either the Petroff or Humphrey patents above enumerated, and the yield of the also useful

sludge sulphonates is not materially affected.

Having described my invention, I desire to be limited only by the ensuing claims:

1. In the process of producing white oil or light colored technical oils, mahogany sulphonates, and sludge layer sulphonates from mineral oil, the step of sulphonating said oil with a fuming sulphuric acid containing between 25 and 35% free sulphur trioxide at a temperature of between 50 and 60° C. 70

2. In the process of producing white oil or light colored technical oils, mahogany sulphonates, and sludge layer sulphonates from mineral oil, the step of treating said mineral oil with fuming sulphuric acid containing 80 between 25 and 35% free sulphur trioxide. 75

In witness whereof, I hereunto subscribe my name.

LATIMER D. MYERS.
